(57) **CLAIM**

The original design for an ear insert and audio communication link, as shown and described.

DESCRIPTION

FIG. 1 is a front elevational view of an ear insert and audio communication link that is adapted to be worn in both the left and right ears of a user and which forms our new design; FIG. 2 is a bottom plan view thereof; FIG. 3 is a rear elevational view thereof; FIG. 4 is a top plan view thereof; FIG. 5 is a right side elevational view thereof; FIG. 6 is a left side elevational view thereof; and, FIG. 7 shows our ear insert being worn in the left ear of a user, the flexible acoustic tubing illustrated in broken lines for coupling the ear insert to an audio receiver being shown for illustrative purposes only and forming no part of our design.
